TUBING CUTTER

Ermon F. Ayer, Mount Carmel, Conn., assignor to General Hardware Mfg. Co., Inc., New York, N.Y., a corporation of New York

Filed May 16, 1960, Ser. No. 60,605

Term of patent 14 years

(Cl. D54—13)

FIG. 1 is a front elevation of a tubing cutter, showing my new design. The front and back of this article are substantially identical.

FIG. 2 is the right end view of FIG. 1.

FIG. 3 is the left end view of FIG. 1.

FIG. 4 is a bottom view of FIG. 1.

FIG. 5 is a perspective view of the tubing cutter.

FIG. 6 is a section taken at line 6—6 in FIG. 1.

FIG. 7—7 is a section taken at line 7—7 in FIG. 2.

I claim:

The ornamental design for a tubing cutter, substantially as shown and described.
